Fig. 5

Fig. 6

Fig. 7

FIG. 1 is a perspective view of article holder for a perforated support board showing my new design;

FIG. 2 is a bottom plan view thereof;

FIG. 3 is a side elevational view taken along lines 3—3 of FIG. 2;

FIG. 4 is a rear elevational view taken along lines 4—4 of FIG. 5;

FIG. 5 is a top plan view thereof;

FIG. 6 is a front elevational view along lines 6—6 of FIG. 5;

FIG. 7 is a side elevational view along lines 7—7 of FIG. 5.

This application is a continuation of my copending application Serial No. D. 73,046, filed January 3, 1963, and now abandoned.

I claim:

The ornamental design for an article holder for a perforated support board as shown and described.
